[57] ABSTRACT

A veterinary obstetric instrument for assisting the birth of fetal animals to avoid the necessity of caesarian operations. The construction of the device comprises a quick-release progressively locked telescoping body portion, a breeching plate and belt for attaching the device to an animal, a ground support member and a positioning handle, dual cables mounted on lever-driven ratchet reels rotatably mounted on a reel bracket, and chain or cable means for attaching the reel mounted cables to the head or body portion of the fetal animal.

DUAL-PULL VETERINARY FETAL EXTRACTOR

The birthing of fetal animals has presented substantial problems for cattlemen and veterinary doctors for many years. This problem has been particularly acute in the beef cattle industry for highly bred heifer cows birthing their first fetal calf. In the absence of assistance, the cow and/or the calf are frequently lost. Powered mechanical tensioning devices are prevalent in the industry to avoid the necessity of caesarian operations. Single-pull ratchet-driven fetal devices are well known to the art and have been utilized for several years.

Difficulties encountered in the utilization of a single-pull tensioning device have led to the concept and design of the invention constituting the subject matter of this application.

One of the objects of this invention was to provide a dual source of mechanical tension to enable the maneuvering of the fetal animal. Another object was to provide snap attached freely rotating butt plate in order not to unduly restrict the movement of the animal. The third object was to provide a quick-release, telescopingly adjustable body portion to give the veterinary complete control over the amount of tension applied to the fetal animal and to instantaneously release all tension if required.

The foregoing objects, among other considerations, led your inventor to design the dual-pull veterinary fetal extractor constituting the subject matter of this invention.

The construction and use of the device of this invention is summarily described as comprising a telescopingly adjustable body. Attached to the forward end of the body portion is a grooved retaining pin which is secured in a snap lock rotating engagement to a butt plate which is secured to the animal by means of a butt plate strap. Mounted on the rear of the telescoping body portion are two reels on which are wound tensioning cables. These two reels are ratchet driven and normally restricted from rotation in one direction by a cog reel which is locked in position by retaining palls. A construction of the individual reel devices well known to the prior art are available on the commercial market, and are used for tensioning fence wire. The body portion and reel mounting frames are supported a few inches above ground level by a ground support attached to the reel mounting frame and/or telescoping body portion. At the extreme rear of the instrument is a positioning handle which is preferably constructed of adequate width to permit grasping with both hands. Immediately adjacent this maneuvering handle is the release knob which is mounted on a release shaft which projects through the telescoping body portion and will contact and release the locking engagement of the inner and outer shafts permitting an instantaneous foreshortening of the telescoping body portion. Additional advantages and objects of this invention will be apparent to those skilled in the art from a study of the attached several views and the following detailed description and claims.

Reference is made to attached view wherein identical referenced characters are utilized to refer to similar or equivalent components throughout the various views and the following description.

FIG. 1 is a perspective view of the complete device assembled.

FIG. 2 is a sectional view of the telescoping body portion taken substantially on line 2-2 on a plane in the direction of the arrows disclosing in detail the construction of the components of the latching device utilized for securing and interlocking the outer and inner shaft of the telescoping body.

FIG. 3 is a fragmented view of the forward end of the telescoping body with the butt plate detached from the device.

FIG. 4 is a sectional view taken substantially on line 4-4 of FIG. 1 looking in the direction of the arrows disclosing in detail the construction of the butt plate catch.

FIG. 5 illustrates a chain-type device which may be used to secure the hook of the tensioning cable to the leg or other portion of the fetal animal.

FIG. 6 is a snarelike noose particularly suited to securing the tensioning cable to the head of the fetal animal.

The device of the preferred embodiment of this invention principally utilizes aluminum in construction to reduce weight and avoid corrosion; however, other type materials or metals might well be utilized. The central, telescoping body portion 5 of this device may be constructed of square tubular aluminum. In essence, all of the components of the device are mounted on or secured to the inner shaft 12 constructed internally of the forward end of the inner shaft 12 is a spring latch 13. The spring latch 13 was constructed with a V-spring 14 which was secured to the inner shaft by a retaining pin 15. At the forward end of the V-spring 14 are constructed latch pins 16 which, in their normal spring-loaded position, project outward through latch holes 17 in the wall of inner shaft 12. Projecting through the entire length of the inner shaft 12 is a release shaft 19. Adjacent the V-spring 14 and secured to the release shaft 19 is a U-shaped release clamp 20. When the release shaft 19 is forced forward by striking the release knob 21, release clamp 20 depresses the V-spring 14 and withdraws the latch pins 16 into the inner shaft 12. When the device is assembled, the outer shaft 1222 is telescopingly mounted over the inner shaft 12. At periodically spaced intervals in the outer shaft 22 are latch pin retaining holes 23. When the inner 10 and outer 22 shafts are telescopingly engaged, release knob 21 removes the U-shaped retaining clamp 20 from engagement with V-shaped spring 14 and the latch pins 16 project outward and lockingly engage the latch pin retaining hole 23 in the outer shaft 22. At the forward end of the outer shaft in elongation of the telescoping body 11 is mounted butt plate retaining 15 pin 24, in its surface is a retaining groove 25. The butt plate 27 includes a socket 28. Rotatably receives butt plate retaining pin 24 and the two components are retained in a snap lock engagement by spring-loaded ball catch 30 which engages retaining groove 25. The butt plate 27 is provided with a butt plate strap 31 for securing the butt plate to an animal. Securely mounted on the rear of inner shaft 12 are the remaining components of the device. Attached to the inner shaft 12 is ratchet mounting frame 32. Rotatably mounted on this frame is the left cable reel 33 and the right cable reel 34. The entire structure is supported above ground level a few inches by means of ground support member 35. Integral with or attached to the ratchet mounting frame 32 is securely attached a broad positioning handle 36 of adequate width to permit the grasping with two hands and adjacent this handle 36 is release knob 21.

As previously stated, the construction of the ratchetlike lever-driven means for rotating the left 33 and right 34 cable reels and their mechanical construction will be described only in summary in that these devices are well known to the art and widely used for stretching fence wire. The cable reels 26 are mounted for rotation on reel shafts 37 which are secured to the ratchet mounting frame 32. One flange of each of reel is constructed with a series of teeth and will be referred to as a ratchet flange 38. In operation, this ratchet flange 38 is engaged and rotated by a lever pall 39. The reels 26 are retained in the rotated or tension position by a spring-loaded stop pall 40. Associated with a lever pall 39 is a small spring-loaded ratchet control lever 41 which is so positioned the lever pall 39 as to place it in or out of the engagement with ratchet flange 38. Secured to each reel 26 is a tension cable 42. In the preferred embodiment, to each cable was secured a cable hook 43 for convenience of attaching the cable 42 to the noose 44 or leg chain 45. A jack handle 46 is mounted for rotation concentric with a cable reel 26 on reel shaft 37 to increase mechanical advantage and apply adequate rotating pressure to a lever palls 39. Lever pall 39 is secured to this jack handle 46 whereas stop pall 40 may be mounted on ratchet mounting frame 32.

70 The foregoing is a reasonably accurate description of construction of the preferred embodiment of the device. In use, butt plate 27 is secured to the bearing animal by butt plate strap 31. Butt plate retaining pin 24 then may be placed in snap engagement with socket 28. As required by circumstances, the noose 44 or leg chain 45 is secured to protruding

portion of the fetal animal and the cables 42 are attached as required by the particular situation. A tensioning of the cables 42 by operation of jack handles 46 by a veterinarian assisting in the birth of the fetal animal may, be selective application of tension as required, facilitate the birth of fetal animal and frequently save the life of fetal calf and/or the bearing animal under conditions when one or both might well die in the absence of professional assistance or the more drastic procedure of caesarian surgery.

Having described the construction of the device and its utilization in detail what is desired to be claimed is all embodiments and equivalents not departing from the scope of the appended claims.

1. A veterinary obstetrical instrument comprising:
  - a. an elongated body member having a rear portion and a forward member, said body portion having various components of the instrument secured thereto,
  - b. a butt plate pivotally secured to the forward portion of said body member, said butt plate constructed and arranged to contact an animal,
  - c. a ratchet mounting frame secured to the rear portion of said body member,
  - d. a first ratchet reel mounted for independent rotation in said ratchet frame,
  - e. a second ratchet reel mounted for independent rotation in said ratchet frame,
  - f. a first means for selectively rotating and securing in position the first ratchet reel,
  - g. a second means for selectively rotating and securing in position the second ratchet reel,
  - h. a first cable secured to and wound on the first said ratchet reel,
  - i. a second cable secured to and wound on the second said ratchet reel,
  - j. a head-securing means secured to the first said cable said means adapted to encircle and grasp the head of a fetal

animal, and

- k. a leg-securing means secured to the second cable said leg-securing means adapted to encircle and grasp the leg or legs of a fetal animal.

5. 2. The invention of claim 1 also comprising a ground support member attached to said body member to support said body above ground level.
3. The invention of claim 1 also comprising a positioning handle secured to the rear portion of said body.
10. 4. The invention of claim 1 wherein said butt plate is secured to the forward portion of said body portion by means of:
  - a. a pin, and
  - b. socket catch securely pivotally engaging said body and said butt plate.
15. 5. The invention of claim 1 wherein the body portion comprises:
  - a. an inner shaft,
  - b. an outer shaft telescopingly engaging said inner shaft, and
  - c. a spring latch selectively securing said inner shaft and said outer shaft in locking engagement.
20. 6. The invention of claim 5 also comprising:
  - a. a release shaft projecting internally of said body,
  - b. a release knob mounted on said release shaft adjacent said rear portion of said body, and
  - c. said spring latch constructed and arranged to be released responsive to pressure on said release knob.
25. 7. The invention of claim 1 also comprising cable hooks securely attached to said cables.
30. 8. The invention of claim 1 wherein said head-securing means and said leg-securing means comprises:
  - a. a noose adapted to secure said cable to the head of a fetal animal, and
  - b. a leg chain adapted to secure said cable to a leg of a fetal animal.
